BY *Fetherstonhaugh & Co.*
ATKINS.

UNITED STATES PATENT OFFICE.

GEORGE ANDREW BOWNESS, OF SUMMERSIDE, PRINCE EDWARD ISLAND, CANADA.

HARNESS.

1,345,577.

Specification of Letters Patent.

Patented July 6, 1920.

Application filed May 6, 1919. Serial No. 295,196.

To all whom it may concern:

Be it known that I, GEORGE ANDREW BOWNESS, a subject of the King of Great Britain, and a resident of the town of Summerside, in the Province of Prince Edward Island, Dominion of Canada, have invented certain new and useful Improvements in Harness, of which the following is a specification.

10 This invention relates to improvements in harness and particularly to saddles, back pads and adjustment of the belly straps, and the objects of the invention are to so construct the harness that in the event of the belly strap breaking adjacent to the saddle then by adjusting the length of the belly strap a new connection may be made, so that the life time of the belly straps is prolonged, and to permit of this adjustment to the belly strap being made under any working conditions, without the necessity of skilled labor being employed.

Further objects are to permit of the trimmings being utilized as the securing means 25 for the upper end of the belly straps, and to permit of ready removal of the trimmings to facilitate the adjustment of the belly strap when broken and thus repair the damage, and to permit the adjustment or renewal of the belly straps being carried out 30 without in any way interfering with the back pad.

Heretofore in harness manufacture it has been usual to construct the saddle of this 35 type with back pads in such a manner that if the belly strap attachment adjacent to the saddle breaks, it is necessary to rip open the back pad to permit of a positioning of new straps and trimmings, an operation which 40 is extremely difficult and can only be accomplished by highly skilled labor.

By the present invention this objection is entirely eliminated, and the harness is much easier to manufacture and can be sewn by 45 means of machinery, whereas, in the older type of harness, the back pads and saddle are hand sewn, which is extremely arduous and tiresome besides involving a considerable loss of time and increasing the cost of 50 manufacture.

With the above and other objects in view the invention consists essentially of the improved construction particularly described and set forth in the following specification, and accompanying drawings forming 55 part of the same.

In the drawings:

Figure 1, is a perspective view of a saddle showing my improved back pads and belly strap attachments, thereon.

Fig. 2, is a fragmentary longitudinal section of the saddle shown in Fig. 1.

Fig. 3, is a plan view of the blank from which the back pads are cut.

Like characters of reference refer to like 65 parts in the several figures.

Referring to the drawings, A represents a saddle, the back 10 of which is constructed of two or more thicknesses of leather or like suitable material, and on the underside of 70 this saddle back pads 11 are secured.

On the under face of the saddle back nuts 12 and 13 are positioned and secured by pins clenched on the outer end, and registering with these nuts are orifices 14 and 15, 75 which extend through the saddle back.

The pads 11 are formed of a blank 16 of leather or other suitable material the lateral edges of which are cut on the bias or tapering inwardly, and in the center of the blank 80 pieces of leather are removed to form a pair of wings 17, the outer edges of which are continuous with the lateral edges of the pads, and the inner edges are formed arcuate as shown at 18.

In the embodiment illustrated the back pads are shown as being made of one piece of leather and the two pads are connected by a strip of leather 19 of less width than the pad cover proper, but it will be evident 90 that each pad may be made individually, that is to say, each pad could be cut from a smaller piece of leather, and the strap 19 would then be joined in the center.

The arcuate edge 18 is sewn to the lateral 95 edge of the strip 19 and the tapered edge of the pad proper is thus brought into direct alinement with the lateral edge of the strip 19, so that the transverse line of sewing by means of which the pad is secured to the 100 saddle back is a continuous straight line, thus making it possible for the sewing to be accomplished by machinery.

The strap 19 is sewn to the center of the underside of the saddle and the wings 17 105 are bent around, so that they may be sewn to the adjacent edge of the strap 19 as shown at 20, the lateral edges of each pad being then sewn to the lateral edges of the saddle while the end or outer edges of the 110 blank will be sewn to the outer edge of the saddle.

The pads will be filled with horse hair or other suitable filling which is used in harness making.

It will be evident that there are no obtrusions or rough edges caused by the sewing of the pads in this manner which would chafe the horse's back, and the surfaces of the pads in contact with the horse's back are smooth and snugly fit thereon.

10 The end edges of the two thicknesses 10 of the leather constituting the saddle back are only sewn for part of the way, so that a passageway or channel 21 is left between the upper and lower thickness 10, and the 15 upper thickness is formed with slits 22 adjacent to the ends each slit communicating with a passageway 21.

10 The belly straps 23 are formed in two portions, and the upper end of each portion 20 will pass through a passageway 21 and through a slit 22, and will be provided with a pair of orifices 24 and 25 which will register with the orifices 15 and 14.

25 The upper end of each belly strap carries a bearing ring 26 and to prevent any undue wear on the belly strap I provide a cover member 27 of suitable material one end of which passes through the slit 22 into the passageway 21, the cover member underlying the upper end of the belly strap.

30 The inner end of the cover member 27 is provided with a pair of orifices 28 and 29, which register with orifices 24, and 15, and 25, and 14, in the belly strap and saddle respectively.

35 The belly strap is held in position by passing a suitable bolt 30 through the orifices 24, 28 and 15, and threading it into the nut 13, and also by passing the threaded end of 40 a turret ring 31 through the orifices 25, 29 and 14, and threading it into the nut 12.

45 In this way the upper end of the belly strap is held rigidly in position.

The bearer ring 26 forms an attachment 50 for the bearer strap 32 which is provided with shaft bearers (not shown in drawings).

55 When this saddle is in use and the inner belly strap 23 breaks or fails adjacent to the ring 26, then all that it is necessary to do, is to unbuckle the belly strap and push the upper end through the passageway 21 to a suitable distance, and then punch two new holes in the upper end of the inner

belly strap to permit the bolt 30 and turret ring 31 (which have been removed, to remove the broken belly strap) being replaced by passing them through the newly punched holes and through the orifices in the saddle A and threading them into the nuts 13 and 12 respectively.

60 The chafing of the ring 26 on the belly strap 23 is prevented by making the wearing or cover member 27 of metal, leather or the like, so that the life time of the belly strap will be prolonged.

65 Any other trimmings that are required may be secured to the saddle A in any manner, but what I particularly desire to emphasize in my specification are the adjustability of the inner belly strap whereby it 70 may be repaired when broken with a minimum of time and labor, the construction of the back pads, whereby chafing of the horse's back is eliminated, and the sewing of the pad in position on the saddle.

75 As many changes could be made in the above construction and many apparently widely different embodiments of my invention within the scope of the claims, constructed without departing from the spirit 80 or scope thereof, it is intended that all matter contained in the accompanying specification and drawing shall be interpreted as illustrative and not in a limiting sense.

85 What I claim as my invention is:

1. A saddle having a passageway in a lateral edge and slit in the outer face, a belly strap having the upper end slidably passing through the said passageway and said slit, readily removable means for securing the belly strap in position, and a ring engaged by the belly strap and saddle, as and for the purpose specified.

90 2. A saddle having a passageway in a lateral edge and a slit in the outer face, a belly strap having the upper end slidably mounted in the passageway and slit, a cover member underlying the belly strap and having its outer edge inserted into the passageway, a ring engaged by the cover member and upper end of belly strap, and readily removable means for securing the upper end 95 of the belly strap in position.

100 In witness whereof I have hereunto set my hand.

GEORGE ANDREW BOWNESS.
